UNITED STATES PATENT OFFICE.

FRANK E. PUTNAM, OF LOWELL, MASSACHUSETTS.

SHEET-MUSIC HOLDER.

SPECIFICATION forming part of Letters Patent No. 251,942, dated January 3, 1882.

Application filed September 28, 1881. (No model.)

To all whom it may concern:

Be it known that J. FRANK E. PUTNAM, of the city of Lowell, county of Middlesex, and State of Massachusetts, have invented a new and useful Sheet-Music Holder, of which the following is a specification.

My device relates to holders for retaining sheet-music in proper position upon the music-rack of a piano when it is in use; and the objects of my invention are to provide a cheap and simple device which can be readily placed upon the music-rack of a piano without injury to it, which can be made to hold the sheets without interfering with their use, and which can be readily removed without the use of tools, and which can be so shifted as not to interfere with the closing of the piano without removing it from the music-rack. I accomplish these objects by the mechanism shown in the accompanying drawings, in which—

Figure 1 is a side elevation with a portion broken away. Fig. 2 is a plan showing the device in place on a music-rack, also how the sheets of music are held by it.

25 A is a spring-clamp, which, when placed upon the edge of a piano music-rack, will clasp it firmly between the plates *a* and *a'*.

Attached to the clamp A is a post, B, extending upward in a line of direction parallel with 30 the plate *a*, which lies flat upon the front of the rack when in position.

Upon the post B is placed a clasp, D, composed of jaws C C, which have ears *e* upon their upper and under edges, through which 35 the post passes, and a spring, *m*, to close the jaws. The sheet metal of which the jaws are formed is bent so as to have the ends *e e* of the two parts bear against one another upon one side of the post to form grasping-jaws capable of bearing upon any thin object placed 40 between them, while upon the opposite side of the post the two parts extend back in wings *f f*, against which the ends of a spring, *m*, placed between them, bear to separate them and close 45 the ends *e e* together.

The person using the device can open the clasping-jaws by pressing the wings *f f* toward one another, when the article can be placed between the ends *e e*, and the wings *f f*, being released, will be forced apart by the spring *m*,

and the article between the clasping ends *e* firmly held until released by again bringing the wings toward one another. The spring *m* is a spiral spring, and is placed upon the post B, between the ears attached to the top and bottom edges of the jaws. It may, however, if desired, be a flat spring with resilient ends placed in contact with the wings *f f*. 55

It is also obvious that the several parts may be constructed of other than sheet metal—as, 60 for instance, wire.

F is the music-rack of a piano.

When the device is to be used it is slipped onto the upper edge of the music-rack or one of its bars, as shown in Fig. 2, and the back 65 of the sheets of music is placed within the jaws with their lower edges resting, as usual, upon the piano. The leaves will then be supported and held together, while they may be turned over in the usual manner without impediment 70 and without danger of their falling apart or sliding down or crumpling, as is frequently the case when the sheets lose any part of their stiffness. There is visible to the person looking at the music from in front no mechanism, 75 because there is no part which overlaps the sheets.

When it is desired to close the piano the clamp D is turned upon the post until the wings are toward the front of the piano, when, 80 the rack being swung down in the usual manner, the wings will be brought into the space over the key-board and the grasping-ends *e* of the jaws will not project above the music-rack sufficiently to come into contact with the piano-top when it is let down. 85

What I claim as new and of my invention is—

1. The combination of the clamp A, bearing the post B, with the jaws C C, provided with ears *e*, through which the post passes, and the 90 spring *m*, substantially as described.

2. The combination of the clamp A with the post B, and clasp D, which has jaws substantially parallel with the bearing-faces of the clamp, substantially as and for the purpose described. 95

FRANK E. PUTNAM.
